ADJUSTABLE SUPPORT FOR YARN
PACKAGESRoy G. Ross, Rockford, Ill., assignor to Barber-
Colman Company, Rockford, Ill., a corporation
of Illinois

Application February 15, 1939, Serial No. 256,437

7 Claims. (Cl. 242—130)

The invention relates to adjustable supports and more particularly to a spool skewer which is adjustable for insertion into the bores of spools or the like of different diameters.

One object of the invention is to provide a spool skewer or yarn package support which may be easily and quickly manipulated to set it for insertion into spool bores of any one of a plurality of different diameters.

Another object of the invention is to provide an adjustable support of the general type indicated which is simple and cheap to make, although rugged and strong in construction.

Further objects and advantages of the invention will become apparent as the following description proceeds, taken in connection with the accompanying drawing in which:

Figure 1 is a perspective view of an adjustable spool skewer embodying the invention.

Fig. 2 is a rear elevation of the device of Fig. 1.

Fig. 3 is a front elevation of the device of Fig. 1 with a yarn package spool of large interior diameter supported thereon.

Figs. 4 and 5 are respectively a front elevation and side elevation of the device of Fig. 1 with a yarn package sleeve and spool thereon having a bore of small diameter, Fig. 5 being partially in section.

The invention has been shown herein as embodied in a skewer or support for yarn packages such as are used in creels for high speed warpers. It will be understood, however, that the skewer herein contemplated is also adapted for other uses and for supporting spools or the like in other types of machines. Although a particular embodiment of the invention has been shown and described in some detail in order to make clear the practice of the invention, there is no intention to thereby limit the invention to such embodiment, but, on the other hand, the appended claims are intended to cover all modifications and alternative constructions within the spirit and scope of the invention.

In the particular construction shown (Fig. 1) the support embodies a channel shaped metal base or bar 10 from which a pair of prongs 11 and 12 project in generally parallel spaced relationship. These prongs are inserted into the interior axial bore within a yarn package spool or sleeve 14 (Fig. 3). By adjustment of the spacing between the prongs 11—12, through the medium of an improved construction herein described, the support is adjusted to accommodate spools of different interior diameters. For example, it may be adjusted with the prongs spaced

as in Figs. 1 and 3 so as to accommodate a yarn sleeve having a relatively large interior diameter or the support may alternatively be adjusted with the prongs spaced more closely together as shown in Figs. 4 and 5 to accommodate a smaller diameter sleeve 14^b. Packages or cheeses of yarn 14^b are wound on such sleeves in a suitable winding machine, for example, and then these packages of yarns are placed in creels and the yarn transferred to a warper beam. For various reasons it is sometimes necessary to use different sizes of spools or sleeves, the smaller size being preferred when the package of yarn is to be dyed after spooling and before being wound on the warper beam. Since the "creeling time," that is, the interval required for placing fresh yarn packages on the creel represents idle time for expensive associated machinery it is requisite that such factors as a different size of yarn package spool or sleeve should interfere as little as possible with the setting up of the creel. Accordingly a quickly adjustable yarn holder support is highly desirable.

The prongs 11 and 12 of the skewer have been shown herein as projecting arms on a corresponding pair of opposed L-shaped brackets, which, for the sake of economy are preferably fashioned as stampings from sheet metal. The lower bracket, designated generally by the numeral 15 (Fig. 1) includes, in addition to the prong arm 11, an angularly disposed base arm 16. This base arm is bolted to the base of supporting bar 10 (Fig. 5) with a spacer collar 17 interposed between the abutting faces of the bracket and base bar. Similarly, the upper bracket, designated generally by the numeral 18, also includes, in addition to its prong arm 12, an angularly disposed base arm 19 which is arranged to lie against the face of the base bar 10. In the case of the upper bracket, however, it is vertically adjustable on the base 10, rather than being rigidly fixed thereon as in the case of the lower bracket 15. For this purpose the base arm 19, on the upper bracket 18, is given a fork shape, being slotted at 20 (Fig. 1) with the arms of the fork straddling the spacer collar 17 (Fig. 2). In this way the spacer collar serves to guide the upper bracket in its adjustable movement and prevents lateral displacement of the lower end of the bracket arm 19.

To hold the upper bracket prong 12 in either of two selected positions of adjustment, with respect to the lower prong 11, a pin and slot connection is formed between the upper bracket and the base bar 10. For this purpose a curved slot

21 (Fig. 2) is fashioned in the base bar 10 and is provided with laterally offset pockets or sockets 21^a at its opposite ends. In this slot rides a projection on the upper bracket 18, shown herein as a pin 22 riveted to the base arm of the bracket (Fig. 5) and having an enlargement 22^a thereon which bears against the inner face of the base bar 10 to prevent the bracket 18 from pulling away from the base bar. The pockets 21^a are disposed in longitudinal alignment with the spacer collar 17 on the base bar 10 so that when the pin 22 is in one or the other of the pockets 21^a the upper prong arm 12 will be disposed in its corresponding upper and lower positions shown respectively in Figs. 1 and 5. A helical tension spring 23, anchored at its opposite ends to the base bar 10 and to the pin 22, yieldably urges the pin into one or the other of the pockets 21^a so that it is firmly seated therein.

As a means of securing the yarn sleeves 14 or 14^a on the skewer prongs 11—12 leaf springs 24 and 25 are provided (Figs. 1 and 5). These leaf springs are bolted to the inner sides of the respective prong arms and are provided with rounded abutments 24^a and 25^a at their outer ends which project through complementary apertures of the prongs so as to engage frictionally the interior surfaces of the sleeves, which are telescoped over the prongs. The ends of the prongs are bent or curved inwardly toward each other (Fig. 5) to facilitate their insertion into the sleeve.

In the operation of the device, if it is desired to support a large yarn package sleeve such as the sleeve 14 (Fig. 3), the skewer is adjusted with the prongs 11—12 spaced wide apart as shown in Fig. 1. To accomplish this adjustment the pin 22 is placed in the upper slot pocket 21^a and is held firmly in such position by the tension spring 23. To move the prongs 11—12 closer together so as to accommodate a smaller sleeve such as the sleeve 14^a the operator grips the upper bracket 18 and pulls it upward and to the right (as viewed in Fig. 1) so as to free the pin 22 from the pocket 21^a and permit it to slide freely down the slot 21. After the pin 22 has been pushed down the slot 21 it is seated in the lower pocket 21^a by the spring 23. During this movement of the upper bracket 18 the lower end of its arm 19 is guided by the spacer collar 17 which it straddles, so that at the completion of the movement the prong 12 is properly aligned in closely spaced relation with the lower prong 11. It is thus apparent that a strong and rugged skewer construction has been provided which can be quickly and accurately manipulated to accommodate yarn sleeves of different sizes.

I claim as my invention:

1. An adjustable support adapted to be inserted into bores of different diameters in yarn sleeves or the like comprising, a pair of L-shaped brackets disposed in opposed relation with the base arms thereof overlying each other and extending in opposite directions and with the other arms thereof projecting in generally parallel spaced relation for insertion into the bore in a yarn sleeve or the like, means on said other arms for engaging a spool placed thereon, a base, one of said brackets being fixed to said base, and means including a pin and slot connection between the other of said brackets and said base for releasably securing the same in any one of a plurality of positions spaced from said one bracket to accommodate sleeves with bores therein of corresponding diameters.

2. An adjustable support adapted to be inserted into bores of different diameters in yarn sleeves or the like comprising, a base, first and second brackets, said first bracket including a prong fixed to said base, said second bracket including a prong generally paralleling that of the first bracket and a base arm overlying said base, said base having a slot therein underlying the base arm on said second bracket and having offset pockets at each end of said slot, said pockets being spaced at different distances from said first bracket corresponding to the difference in diameter of the bores of the sleeves into which said prongs are to be inserted, a projection on said second bracket slidable in said slot and means for yieldably retaining said projection in one pocket or the other to thereby hold said prongs in selected spaced relation for insertion into sleeve bores of corresponding diameters.
3. An adjustable support adapted to be inserted into bores of different diameters in yarn sleeves or the like comprising, a base, a first bracket forming a prong projecting from said base, a second bracket of L-shape with one arm forming a prong projecting from said base in generally parallel spaced relation with said first bracket prong, the other or base arm of said L-shaped bracket being of fork shape and disposed to straddle a portion of said first bracket structure, said base having a slot therein underlying the base of the second bracket and having laterally offset pockets at each end of said slot, said pockets being spaced different distances from said first bracket corresponding to the difference in diameter of the bores of the sleeves into which said prongs are to be inserted, a projection on said second bracket slidable in said slot, and means including a spring for yieldably urging said second bracket laterally to retain said projection seated in one of said laterally projecting pockets or the other, to thereby hold said prongs in selected adjusted spaced relation for insertion into sleeve bores of corresponding diameter.
4. An adjustable support adapted to be inserted into bores of different diameters in yarn sleeves or the like comprising a base, a first bracket forming a generally flat sheet metal prong projecting from said base, a second sheet metal bracket of L-shape with one generally flat arm forming a prong projecting from said base in generally parallel spaced relation with said first bracket prong, the other or base arm of said L-shaped bracket being of fork shape and disposed to straddle a portion of said first bracket structure, said base having a slot therein underlying the base of the second bracket and having laterally offset pockets at each end of said slot, said pockets being spaced different distances from said first bracket corresponding to the difference in diameter of the bores of the sleeves into which said prongs are to be inserted, a projection on said second bracket slidable in said slot, means including a spring for yieldably urging said second bracket laterally to retain said projection seated in one of said laterally projecting pockets or the other to thereby hold said prongs in selected adjusted spaced relation for insertion into sleeve bores of corresponding diameter.
5. An adjustable support adapted to be inserted into bores of different diameters in yarn sleeves or the like comprising, a base, one of said brackets being fixed to said base, and means including a pin and slot connection between the other of said brackets and said base for releasably securing the same in any one of a plurality of positions spaced from said one bracket to accommodate sleeves with bores therein of corresponding diameters, leaf springs fixed to the inner faces of each of said prongs adjacent the inner ends thereof and extending toward the projecting ends thereof, each of said prongs being apertured, and abutment heads on each of said leaf springs projecting through said apertures for yielding frictional

engagement with a sleeve into which the prongs are inserted.

5. An adjustable support for a yarn sleeve or the like comprising, in combination, a prong having a projection on the base portion thereof, a base having at least two spaced sockets therein each dimensioned to receive said projection to define two alternative positions for the prong on the base, a second prong mounted in spaced relation to the first prong, and spring means operative to hold said projection releasably in either socket.

6. An adjustable support for a yarn package having a hollow core, comprising, in combination, a supporting member having an elongated slot therein, a prong projecting from the support and having a part guided for movement along said slot, said slot being shaped at spaced points along its length to form recesses for receiving

said part, spring means acting on said part to hold it releasably in any one of said recesses, and a second prong secured to the support and projecting therefrom in spaced parallel relation to the first prong irrespective of the position of the latter relative to said slot.

10 7. An adjustable support for a yarn package having a hollow core, comprising, in combination, a supporting member having a slot therein, a prong projecting from the support substantially perpendicular thereto, said prong having a part guided for movement in said slot, spring means acting on said part to hold it yieldably at either end of said slot, and a second prong secured to said support and projecting therefrom in spaced parallel relation to the first mentioned prong irrespective of the position of the latter relative to said slot.
